CHARLES E. KLAUS, OF PORTLAND, OREGON

FOUNTAIN PEN

Application filed May 29, 1930. Serial No. 457,031.

This invention relates to improvements in fountain pens, and it consists of the constructions, combinations and arrangements herein described and claimed.

5 An object of the invention is to provide an auxiliary ink reservoir for fountain pens, the contents of which may readily be discharged into a main reservoir when the latter runs dry, the necessity for drawing upon the auxiliary reservoir serving as an indication that the fountain pen requires refilling.

Another object of the invention is to improve the so-called self-filling fountain pen to the extent of providing main and auxiliary 15 reservoirs, and a novel arrangement of presser strips operable by a common lever either for the simultaneous filling of both reservoirs or the emptying of the contents of the auxiliary reservoir into the main reservoir.

20 A further object of the invention is to improve the dual reservoir or ink sac, thus involving a process according to the steps of which the resultant sac is not only divided into main and auxiliary reservoirs but in 25 producing the point of constriction an objectionable lateral enlargement or distortion which would prevent the easy insertion of the sac in the pen barrel is avoided.

Other objects and advantages appear in 30 the following specification, reference being had to the accompanying drawings in which

Figure 1 is a perspective view of a fountain pen, particularly illustrating the actuating lever.

35 Figure 2 is a vertical section of a portion of the pen barrel showing the compressor mechanism in the position that it assumes when both reservoirs of the ink sac are distended and presumably full.

40 Figure 3 is a similar view illustrating one action of the lever by which both reservoirs are compressed simultaneously preparatory to being filled.

45 Figure 4 is a view similar to Figure 3 illustrating the reversal of the actuating lever whereby only the auxiliary reservoir is compressed thereby to discharge the contents into the main reservoir.

50 Figure 5 is a cross section taken on the line 5—5 of Figure 2.

Figure 6 is a perspective view of the lever supporting spring, the function of which is to positively hold the lever in its rest position as in Figure 2.

Figure 7 is a perspective view of the main 55 presser strip.

Figure 8 is a perspective view of the auxiliary presser strip.

Figure 9 is a perspective view of the actuating lever.

Figure 10 is a plan view of a portion of the ink sac illustrating the preliminary step of constriction.

Figure 11 is a plan view of a portion of the ink sac illustrating the formation of an ink 65 duct by the step of vulcanization.

Figure 12 is a cross section taken on the line 12—12 of Figure 11.

This invention is concerned with relieving the annoyance attendant upon having a fountain pen suddenly run dry at a critical moment. It is a matter of frequent occurrence to have the supply of ink suddenly give out while in the midst of a signature or some other and perhaps important writing.

To say the least, this is an inconvenience. The writer is thereby required to reach for the ink bottle and refill his pen. This not only means the loss of some time, but it is easily conceivable that in some instances the 80 person concerned might be embarrassed.

The remedy herein proposed is to provide the barrel 1 of a fountain pen with a dual reservoir or ink sac 2 of rubber or other appropriate flexible material which is divided 85 into main and auxiliary reservoirs 3 and 4 by means of a constriction 5, the making of which is the subject of an ingenious process. This ink sac is adapted to be acted upon by a compressor mechanism generally denoted 6, 90 and it is in this that a large part of the novelty resides.

A slot or other opening 7 located somewhere near the closed end 8 of the barrel 1 has fixedly combined therewith (Fig. 5) and 95 located medially thereof a pin 9. An actuating lever 10 is pivotally and slidably mounted on the pin for which purpose the lever has a slot 11 for the reception of the pin.

The lever 10 is in the nature of a solid bar 100

(Fig. 5) but might be struck up from sheet metal bent to the proper proportions. Its ends 12, 13 are reduced by shaping away the material on the nether or inner edge until the 5 extremities are approximately as thick as the pen barrel (Fig. 2). These shaped places provide recesses in which the protrusions 14, 15 of a lever supporting spring 16 bear to maintain the lever in its proper resting position (Fig. 2) when the dual reservoir 2 is fully distended.

It is not necessary for the protrusions 14, 15 to fit the recesses adjacent to the ends 12, 13 exactly. They need only to bear against 15 the ends of the lever 10 thus keeping the latter level in its slot 7. Either end of the lever may be depressed in the slot 7 by the thumb nail, depending on whether it is desired to compress both reservoirs 3, 4 prior to filling 20 (Fig. 3), or only the auxiliary reservoir 4 (Fig. 4) in order to discharge the contents into the main reservoir 3. The lever 10 thus becomes the selecting means by which either all or only one of the reservoirs is compressed. 25 These actions involve the use of a lug 17 on the exposed edge of the lever 10, which is adapted to be engaged by the thumb nail to slide the lever 10 in one or the other direction preparatory to exercising the required 30 pressure on the ink sac.

It is observed that the protrusions 14, 15 are bent into form at the ends of a slot 18 in the spring 16. The spring is slit and parts of the metal are bent up into the shape of protrusions. The ends 12, 13 of the lever 10 work in the slot either for the simultaneous compression of the two reservoirs 3, 4 (Fig. 3) or the compression of only the reservoir 4 (Fig. 4).

40 That end of the spring 16 adjacent to the slot 18 has an arm 19 which carries a circular yoke 20 (Fig. 6) which fits the pen barrel thus to establish an adequate support not only for the spring 16 but the entire inner component of the compressor mechanism 6. This inner component consists of the spring 16, already mentioned, a main presser strip 21 and an auxiliary presser strip 22. The purpose of the strip 21 is to compress the main 45 reservoir 3, while the purpose of the strip 22 is to compress the auxiliary reservoir 4.

The main presser strip 21 is riveted or otherwise secured at one end to the spring 16 as at 23. The other end has a bifurcation 24 55 (Fig. 7) to the insides of which ears 25 (Fig. 8) of the auxiliary presser strip 22 are pivoted, the approximate extent of pivotal motion of one strip to the other is shown in Figure 4.

A transverse groove 26 stamped in or 60 struck across the main presser strip 21 prior to furcating the adjacent end permits of easier manufacture of the presser strip, especially as it may be desired to have the upper or inner edge of the strip made slightly 65 higher than the flat portion in the imme-

diate region of a slot 27 in the presser strip. The ends 12, 13 of the lever 10 pass into this slot during the working of the lever 10 as seen in Figures 3 and 4.

One end of the auxiliary presser strip 22 is bent up at 29 to provide a rest which bears 70 against the under side of the lever supporting spring 16 (Fig. 2) and tends to relieve the auxiliary reservoir 4 of the weight and pressure. This rest is part of a reduced end 75 30 of the auxiliary strip 22 (Fig. 8) which is adapted to swing between the furcations 24 to a slight extent (Fig. 4). The opposite end of the strip 22 is forked at 31 (Fig. 8), and at the inner end of the fork there is a stop 32 with the opposite sides of which 80 the lever ends 12, 13 are adapted to engage (Figs. 3 and 4) to limit the swinging or raising movement of the lever 10.

85 A depression 28 stamped from the material of the strip 21 at one end of the slot 27 extends into the fork 31 under the circumstances in Figures 2 and 3. The end of this depression clears the adjacent stop 32 of the strip 22. The purpose of this depression is to enable the use of a shorter lever stop 32 than would otherwise be possible. Another 90 effect of this depression is a greater capacity of reservoirs 3, 4.

95 This is easily understood. The lever 10 must clear the stop 32 while in its resting position (Fig. 2), but when the lever 10 is swung in one or the other direction (Figs. 3 and 4) its ends 12, 13 must engage one or the other side of the stop. If the strip 21 were left perfectly straight up to the point of the stop 32 it follows that the latter would have to be longer in order to be in a position where the ends 12, 13 can engage it. By depressing the strip at 28 the stop 32 is in effect reduced to a lower location, enabling the spring 16 to move the main presser strip 21 farther out toward the lever 10 (Fig. 2) and thus making possible a greater capacity 100 of the ink reservoirs 3, 4.

105 Thus far the operation of the compressor mechanism is readily understood. Consider the position in Figure 2 and assume that it is desired to refill the ink sac 2. The thumb nail of the right hand is placed edge-on 110 against the lever 10 at a point near the end 12 and pressed in. This raises the end 13 above the surface of the barrel 1. The thumb nail is then slid along the lever 10 until it comes in contact with the lug 17, whereupon 115 a continued push will slide the lever over the pin 9 by virtue of the slot 11 until the pin occupies the front end of the slot.

120 It is now an easy matter to raise the end 12 with the fore finger of the right hand, 125 using the pin 9 as a pivot, until the position in Figure 3 is assumed. The lever end 12 rides against the main presser strip 21, and since the auxiliary strip 22 cannot move by virtue of bearing against the bridge portion 130

33 between the bifurcation 24 and slot 27, the result is a simultaneous depression of both reservoirs 3, 4 (Fig. 3). The pen point 34 (Fig. 1) is now dipped into the ink, and upon a motion of the lever to its original position, by which a release of the dual reservoir 2 is effected, ink will be drawn in.

Upon desiring to transfer the contents of the auxiliary reservoir 4 into the main reservoir 3 the foregoing operation of the lever 10 is reversed. The end 13 is now first pressed in so that the lever can be slid until the pin 9 occupies the other end of the slot 11, whereupon the lever is turned (Fig. 4) so that the end 13 rides against the auxiliary presser strip 22 and turns that independently of the main strip 21. Pressure is applied to the reservoir 4 only with the result that the ink is emptied into the main reservoir 3.

The construction of the ink sac is an important factor of the invention. It has been found that the making of the constriction 5 by molding is virtually impossible, or at best so difficult as to make the cost prohibitive. The alternate choice is to take a tubular ink sac and vulcanize it together at a designated spot so as to produce the constriction. This has the disadvantage of spreading or flaring the sides of the sac so that insertion into the barrel 1 becomes difficult.

The remedy consists of initially molding the sac 2 with a slight constriction 35 (Fig. 10). This is easily accomplished. The constriction 35 is then pressed down and acted upon by an appropriate vulcanizing instrument so that a vulcanized spot 36 (Fig. 11) is produced. The attendant spreading of the constriction 35 is kept within the bounds of the cylindrical sac 2 (Fig. 11) so that there will be no difficulty whatever in inserting the sac in the barrel 1.

The vulcanizing is done in such a manner that one or more ducts 37 (Figs. 5 and 12) are produced. It is through these that the ink 45 flows from the reservoir to the other. The vulcanized spot 36 (Fig. 11) is to be identified as the constriction 5 (Fig. 2), and according to the position of the compressor mechanism 6 it will be seen that the latter can be worked without in any way interfering with the constriction 5 or, more especially, with the ducts 37.

It is obvious that a number of possible variations of the fundamental idea may be carried out in practice. For instance, instead of producing the ink duct or ducts 37 by vulcanization it is possible to use a metal clip to hold the two walls of the sac together, forming either one or two ducts as desired. Or, instead of vulcanizing the walls together, they might be cemented to equally good effect.

The important thing is to form the ink channels or ducts 37 by holding the opposite 65 walls of the sac together in such a way as to

form one or more connecting channels between the main and auxiliary reservoirs. Each duct must be of sufficiently small cross section so that the surface tension of the ink will be great enough to prevent its flowing 70 out of the auxiliary reservoir until forced out by the presser strip.

While the construction and arrangement of the improved fountain pen is that of a generally preferred form, obviously modifications and changes may be made without departing from the spirit of the invention or the scope of the claims.

I claim:—

1. A fountain pen having a barrel with an opening, resilient means having means providing its support in the barrel, a pair of connected pressers of which one is joined with the free end of the resilient means, an ink sac consisting of a pair of connected reservoirs 80 situated between the pressers and a wall of the barrel, and means mounted to turn in the opening to engage either one or the other of the pressers respectively to compress both reservoirs or only one reservoir. 90

2. A fountain pen having a barrel with an opening, resilient means mounted in the barrel, a pair of connected pressers of which one is joined with the free end of the resilient means, a pair of connected reservoirs which the respective pressers are adapted to act upon, and means operating in the opening with sliding and turning motions to reach and actuate either one or the other of the pressers. 95

3. A fountain pen having a barrel, a plurality of connected reservoirs, an equal plurality of connected pressers for the respective reservoirs, and a single lever movable into a plurality of positions for producing a cumulative action of the pressers against the reservoirs or only a single action of one of the pressers against the respective reservoir. 105

4. A fountain pen having a barrel with an opening, a pin associated with the opening, a plurality of ink reservoirs in the barrel, connected pressers movably supported in the barrel adjacent to the reservoirs, and a lever occupying the opening having a slot receiving the pin to enable diverse movements and turning motions whereby to engage the opposite ends of the lever with one or the other of the pressers for either a cumulative or single compressing action. 110

5. Compressor mechanism for fountain pens comprising a reservoir presser, an actuating lever movably mountable in the opening of a pen barrel for operating upon the presser, said lever having an end reduced to provide a recess, and resilient means for yieldably supporting the presser, said means having a protrusion for engaging in said recess against said end to maintain the lever in a normally nested position in the opening. 125

6. Compressor mechanism for fountain 130

pens comprising a main reservoir presser, an auxiliary reservoir presser connected therewith and having a stop, means by which the main presser is movably mounted in a pen barrel having an opening, and a lever swingable in either of two directions through said opening to actuate one or the other of the pressers for a compressing action, the swinging of said lever being limited by engagement 10 with opposite sides of said stop.

7. Compressor mechanism for fountain pens comprising a pair of connected pressers, resilient means with which one of the pressers is connected, being mountable in a pen barrel, 15 and a rest on one of the pressers to engage a portion of the resilient means when the latter is in a relaxed position.

8. A compressor mechanism for fountain pens comprising a slotted lever mountable 20 upon a pin adjoining an opening in a pen barrel, a pair of connected pressers against either of which the respective ends of the lever are movable, a lug on the lever to receive sliding pressure preparatory to a turning motion on the lever for the operation of either presser, and resilient means with which one of the pressers is connected for the support of both pressers said means having protrusions normally bearing against the opposite ends of the lever to maintain its position.

9. A dual reservoir comprising a tubular sac having a portion of the walls secured together to define a reduced fluid duct.

10. The herein described process consisting 35 of slightly constricting a portion of a tubular sac, pressing the constriction together, and vulcanizing the walls of the constriction together at the pressure point thus to produce a reduced duct.
